G. A. LYON.
SUPPORT FOR BUFFERS FOR MOTOR CARS.
APPLICATION FILED MAR. 10, 1916.

Patented Oct. 21, 1919.

INVENTOR
GEORGE ALBERT LYON
BY HIS ATTORNEY Harry Smith

UNITED STATES PATENT OFFICE.

GEORGE ALBERT LYON, OF PHILADELPHIA, PENNSYLVANIA, ASSIGNOR TO LYON NON-SKID COMPANY, OF PHILADELPHIA, PENNSYLVANIA, A CORPORATION OF PENNSYLVANIA.

SUPPORT FOR BUFFERS FOR MOTOR-CARS.

1,319,099.

Specification of Letters Patent. Patented Oct. 21, 1919.

Application filed March 19, 1916. Serial No. 83,275.

To all whom it may concern:

Be it known that I, GEORGE ALBERT LYON, a citizen of the United States, residing in Philadelphia, Pennsylvania, have invented 5 certain Improvements in Supports for Buffers for Motor-Cars, of which the following is a specification.

One object of my invention is to so construct a buffer support for motor cars as to 10 provide for the firm support of the buffer upon the side bars of the car frame irrespective of the cross sectional shape or dimensions of said frame bars, a further object being to provide for raising and lowering the 15 buffer while still maintaining the rigid support of the same on the frame of the car.

In the accompanying drawing—

Figure 1 is a side elevation of a buffer support constructed in accordance with my invention, and of part of the frame of the car upon which said support is mounted;

Figs. 2, 3, 4 and 5 are similar views illustrating other forms of support in accordance with my invention;

Fig. 6 is a transverse section on the line *a—a*, Fig. 1;

Fig. 7 is a transverse section on the line *b—b*, Fig. 2;

Fig. 8 is a view, partly in plan and partly 30 in section, on the line *c—c*, Fig. 4;

Fig. 9 is a transverse section on the line *d—d*, Fig. 4;

Fig. 10 is a face view of the securing bar shown in Figs. 1 and 6, and

Fig. 11 is a view similar to Fig. 7, but illustrating a modification of my invention.

Figs. 6 to 11 inclusive are on a larger scale than Figs. 1 to 5, inclusive.

In the drawing, 1 represents part of one 40 of the side frames of the car. In the buffer support shown in Figs. 1, 6 and 10 of the drawing, the upper and inner sides of the frame 1 are engaged by members 2 and 2^a of a right-angled bar *x* and the other sides 45 of the frame are engaged respectively by the members 3 and 3^a of a right-angled bolt *y*, the members 3 and 3^a of said bolt passing, respectively, through the members 2 and 2^a of the bar *x* and being threaded for the 50 reception of nuts whereby the member 3 of the bolt is caused to exert downward pressure upon the member 2 of the bar and the member 3^a of the bolt is caused to exert lateral pressure upon the member 2^a of said 55 bar so as to pull upon said bar in two di-

rections one at a right angle to the other, thereby confining the same firmly to the side frame of the car irrespective of the cross sectional shape and dimensions of said side frame, it being understood, of course, that 60 the openings in the members of the bar for the passage of the members of the bolt are elongated to permit such movement of the bar and bolt in respect to one another as to provide for the adaptation of the same to 65 frames of different sizes.

Extending upwardly from the member 2 of the securing bar *x* is a web 4 and along-side of the same is located a rearwardly extending member 5 of the buffer, which may 70 be of any desired construction, such for instance as that shown in my Patent 1,198,246, of September 12, 1916.

The adjoining faces of the member 5 and web 4 are ribbed, grooved, or otherwise 75 roughened, as shown in Fig. 10, so that when the two are drawn together laterally by means of a transverse bolt 6 and nut 7 the member 5 of the buffer will be rigidly held in place on the web 4 so as to retain 80 the buffer rigidly in vertical position, the vertical adjustment of the buffer, however, being permitted by first loosening the nut 7 on the bolt 6 so as to free the roughened faces of the web 4 and member 5 from engagement with each other, and, after readjustment of the buffer, being again tightened so as to draw these roughened faces 85 again into engagement with one another.

Instead of employing a special bar *x* 90 for securing the rearwardly extending member 5 of the buffer to the vehicle frame said member 5 may itself be bent, as shown in Figs. 2 and 7, so as to present members 2 and 2^a for bearing, respectively, against the 95 bottom and inner sides of the frame, said members being slotted for the reception of the respective portions 3 and 3^a of the confining bolt, and retention of the forward bar of the buffer in different vertical positions being, if desired, effected by the insertion, between the members 2 of the bar and the under side of the vehicle frame, of a wedge-shaped filling block 8, as shown in Fig. 3.

In case it is not advisable to weaken the buffer bar 5 by the formation of slots therein said bar may be secured to the frame of the car by the use of a pair of confining bolts *y* one in front and one in the rear of

105

110

the bar, the members 3 and 3^a of these bolts passing, respectively, through openings near the ends of bars 9 and 9^a bearing, respectively, against the members 2 and 2^a of the bar 5, as shown in Figs. 4, 8 and 9, and, in order to facilitate vertical adjustment of the forward member of the buffer, the member 2^a of the bar 5 which bears against the underside of the frame 1 may present a convex upper surface, as shown in Fig. 5.

In Fig. 11 of the drawing I have shown a modification of my invention in which separate bolts 10 and 10^a take the place of the angle bolt *y*, the heads of these bolts engaging the flanges of an angle bar 11 which has a bearing upon the upper face of the frame bar 1, the bolt 10^a serving to impart lateral pressure to the member 2^a of the securing bar and the bolt 10 serving to impart upward pressure to the member 2 of said bar.

I claim:

1. A buffer support for motor cars comprising a rigid right angled bar having members to closely engage the top and side faces of the channeled car frame, there being slots in the ends of said members to form slotted substantially rigid ends projecting beyond the faces of the car frame engaged by said members, a substantially rigid right angled bolt having ends projecting through the slotted ends of said members and closely engaging the other faces of the car frame, cooperating nuts to clamp said bolt and bar together so that they conjointly closely encircle the car frame, an integral projecting corrugated web on said bar to project up-

wardly from the car frame and means for detachably and rigidly securing a buffer member to said web.

2. A buffer support for motor cars comprising a rigid right angled bar having members to closely engage the top and side faces of the car frame, there being apertures in the ends of said members to form apertured substantially rigid ends projecting beyond the faces of the car frame engaged by said members, a substantially rigid right angled bolt having ends projecting through the ends of said members and closely engaging the other faces of the car frame, cooperating nuts to clamp said bolt and bar together so that they conjointly closely encircle the car frame, and means for detachably and rigidly securing a buffer member to said bar.

3. A buffer support for motor cars comprising a bar having members at an angle to one another and disposed on corresponding faces of the car frame, means for exerting lateral pressure upon one member of said bar and vertical pressure upon the other member thereof, a projecting web on said bar, a member of the buffer lying alongside of said web, and means for rigidly confining said buffer member to said web.

In testimony whereof, I have signed my name to this specification, in the presence of two subscribing witnesses.

GEORGE ALBERT LYON.

Witnesses:

ALYS MAYER,
MAUD DRUNMOND.
